J. P. MÜLLER.
AUTOMATIC LIFE SAVING APPARATUS.
APPLICATION FILED OCT. 10, 1917.

1,329,990.

Patented Feb. 3, 1920.

UNITED STATES PATENT OFFICE.

JEAN PIERRE MULLER, OF LE HAVRE, FRANCE.

AUTOMATIC LIFE-SAVING APPARATUS.

1,329,990.

Specification of Letters Patent.

Patented Feb. 3, 1920.

Application filed October 10, 1917. Serial No. 195,720.

To all whom it may concern:

Be it known that I, JEAN PIERRE MULLER, a subject of the Grand Duke of Luxemburg, residing at 1 Rue Joseph Clerc, Le Havre, in the Republic of France, have invented a new and useful Automatic Life-Saving Apparatus, of which the following is a specification.

This invention relates to apparatus such as inflatable collars and belts which are used for saving life at sea, of the type which act automatically on contact with water to inflate the collar or belt with air or other gas under compression, the release of the gas being effected by the softening with water of an absorbent substance such as paper, which until softened is adapted to maintain the device in its inoperative position.

The apparatus hereinafter described is designed to effect improvements in this type of apparatus.

The apparatus serves equally for the inflation of buoys thrown to a distance from small guns and carrying ropes, and in this modification is flexibly attached to a wooden stem of the same caliber as that of the gun from which it is fired.

Larger forms of the apparatus may not only protect aviators, but also serve to maintain on the surface of the water, machines adapted for flying over land which may have a breakdown during a crossing, a plurality of large forms of the apparatus being attached to the wings or fuselage of the flying machine, the inflatable chambers being enclosed in a network of wire or cord to withstand the pressure of the water, when on immersion they inflate to function in the same manner as the floats of a waterplane. During flight and while the device is inoperative they offer far less resistance to the air than such floats whereby the speed of the flying machine may be increased.

In the accompanying drawings which illustrate the invention,

Figure 1 is a sectional elevation of an apparatus constructed according to this invention.

Fig. 2 is an outside elevation of the same. Figs. 3 and 4 are detail plans of the disks, showing the striker in section.

The apparatus comprises a thin tube of steel or other metal, A. A steel striker F is disposed within a special spring G in the tube A. The spring G bears against a fixed disk I², and a movable disk I fixed on the striker F for which it serves as a

guide. The disks I and I² are shown to the right of Fig. 1 in plan. The disk I is soldered to the striker F. I² is maintained in place by four pins I³ mounted in four small grooves, which pins prevent the disk from turning, being maintained in place by the pressure of the spring G.

The portions cut away around the edge of the disks I and I² enable the striker F to be easily inserted in and removed from the tube A, while they also prevent compression of air during percussion.

A hook H is provided at the end of the striker F adapted to engage a cam N fixed on a spindle J which passes out through the wall of the tube A. A lever M is fixed upon the spindle J outside the tube A and carries a stud 18. A stud P' is mounted on the outside of the tube A as shown on the drawings, and an absorbent ring P is passed around the studs 18 and P'.

The spring G through the striker F, the hook H, and the cam N tends to turn the lever M away from the stud 19 which movement is prevented by the paper ring P.

A reservoir Q containing compressed air or other gas is disposed within the tube A. The neck of such reservoir is hermetically sealed into the conical end of a tube S by means of a rubber sleeve R aided by a stopper T fixed by means of a bayonet joint or screw which compresses the rubber sleeve into the conical opening of the tube S.

R' is a spiral spring made of a few turns, serving for the ejection of reservoirs after opening of the cover T.

Covers T on the tube A are provided with rubber rings T' inside the cover which render the apparatus water-tight, and the lower one of which serves as a rest for the reservoir Q. A perforator U is disposed within the sleeve V and adapted to perforate the metal stopper of the reservoir Q. The point of the perforator U is beveled and perforated by a hole or groove of a diameter of about $\frac{1}{8}$ millimeter to allow the escape of air or other gas compressed in the reservoir Q after perforation of its metal stopper. The space existing between the perforator and the sleeve V is rendered air tight by aid of a small rubber tube U', a part of which engages on an enlarged portion of the sleeve and the other part on the perforator which, while completely air-tight may be moved downward for the perforating operation. An outlet pipe W communicates with the sleeve V and is adapted to carry the air or

gas from the reservoir Q past a double acting valve into the collar which is to be inflated.

The double acting valve will now be described. This valve connects the apparatus to the collar by means of the milled tube 2, which enters the small tube 4 and is retained there by threads. A rubber ring 3 fills the space between them. 5 is the actual valve of the collar. 6 is a hole for inflation by the mouth. 8 is a valve tube covered by a small rubber tube 10 in the manner of a bicycle wheel valve and operates during automatic inflation. 11 is the vent by which air or gas escapes, reaching the collar by the tube 9.

The novel arrangement of this double valve permits easy attachment of the apparatus to the collar, while the latter remains inflated, and further allows said collar to be inflated, or reinflated with the mouth. The collar can therefore be used even if the gas or air receptacles are missing, or if it is necessary to reinflate.

The operation of the device is as follows:—

25 When the apparatus is immersed in water the paper ring P soaks up the water and breaks by the pressure of the lever M due to the spring G. The lever M by turning, turns the cam N and releases the striker F. 30 The striker F moves downward under pressure of the spring G and strikes the perforator U. The perforator U pierces the metal stopper of the reservoir Q and air escapes through the perforation or groove in the 35 point of the perforator U, through the outlet pipe W past the double acting valve, and inflates the collar to which the apparatus is attached.

To set the device, the cord F³ is pulled. 40 This cord is connected to the striker F and lifts the same to reengage the cam N. A new absorbent ring is placed over the studs 18 and P'. A new air or gas reservoir is provided, or the old one refilled, and the apparatus is then ready for use.

The absorbent ring P is preferably formed of three or four lays of paper known as "hydrophite" being a form of absorbent paper of a smoother and stronger texture 50 than that of blotting paper of which the last layer is fixed by heat with rubber thereby rendering unfastening by a humid atmosphere impossible.

The ring of three layers employed will resist when dry a pull of about 12 kilograms; when very moist it resists no more than 2 kilograms, and when quite wet will break under the strain of about 800 grams. Now the pull on the lever N is about 1200 grams 60 which may be diminished by lengthening the arm of the lever. This results in that even when in a very moist condition the apparatus will not act in an inopportune moment, the rupture being produced only by direct contact with water.

Instead of the absorbent material above referred to, the lever M may be retained by other materials, for example, sugar which functions less rapidly (10 to 12 seconds) this being useful for those who dive to save drowning persons, which would be difficult with apparatus inflated immediately upon contact with water.

A hinged cover 17 is provided over the lever M, protecting the absorbent ring 75 against rain or spray and carrying on its upper end a valve 12 and at its lower end a half tube 13, which allow water to enter and come into contact with the ring when the apparatus is immersed but protect the paper 80 perfectly against rain or spray. 14 is a bolt provided at its head with a hook to receive a wire looped around the absorbent ring by which said ring may be broken manually. In pressing the bolt downwardly by means 85 of the milled nut 15 the ring is broken, and the apparatus parts.

The bolt 14 the upper part of which carries the nut 15 slides in a small tube the upper part of which is split to guide the wire 90 when the nut 15 is depressed to operate the device and to leave a passage for the attachment of the wire to the bolt.

This apparatus may be carried without a pocket which simplifies its manipulation. 95

A spring clip 16 on the back of the tube A is provided for fixing the apparatus upon a sailor's clothing.

If it be desired to break the absorbent ring manually, to start the apparatus in operation, this can be done by pulling upon a cord P² which is attached to said ring.

Having now particularly described and ascertained the nature of my said invention and in what manner the same is to be performed, I declare that what I claim is:— 105

In apparatus of the class described, a casing, means in one end of the casing to hold a reservoir, a perforator, spaced guide disks in the casing, a striker guided by said disks 110 and arranged in line with the perforator, and provided, at the end farthest from the perforator with a notch, a spring to project the striker when the latter is released, striker detaining means including a member to engage the notch of the striker and also including a lever member, a soluble member arranged exteriorly of the casing and coacting with the lever member to normally hold the striker in retracted position, and a cover 115 hinged to the casing, to close thereagainst and inclose the lever and soluble member, said cover having a valve and a water inlet member.

In testimony whereof I affix my signature, 125 in presence of two witnesses.

JEAN PIERRE MULLER.
